UNITED STATES PATENT OFFICE

WILLIAM E. BARLOW, OF TREVOS, PENNSYLVANIA, ASSIGNOR TO HENRY A. DYGERT,
OF PHILADELPHIA, PENNSYLVANIA.

COATING APPARATUS.

Application filed October 6, 1923. Serial No. 686,931.

My invention relates to coating apparatus more especially of a type useful in coating articles, such as receptacles of paper or cardboard designed for dispensing food products or beverages, with a surfacing of paraffine or the like so as to make them impervious to liquids.

My invention is directed chiefly toward provision of an apparatus of the character defined whereby the operation of coating articles of hollow configuration may be carried on in a continuous manner with assurance of complete and uniform coating of the articles, both interiorly and exteriorly, notwithstanding economical use of the coating material.

Other objects and attendant advantages of my invention will be readily apparent from the detailed description which follows of a typical embodiment thereof, and its scope as readily understood from the appended claims.

In the drawings, Fig. I is a perspective view of a coating apparatus or machine conveniently showing my invention.

Figs. II and III when taken together constitute a complete longitudinal sectional elevation of the structure.

Fig. IV is a transverse section taken as indicated by the arrows IV—IV in Fig. III.

Fig. V is a fragmentary detail view on an enlarged scale of a portion of the drive mechanism for the conveyor whereby the articles are carried through the apparatus, and showing also associated instrumentalities for actuating the means whereby the articles are stripped from the conveyor after coating.

Fig. VI is a detail view in perspective showing the manner in which the individual holder clips for the articles are supported in serial groups crosswise between the sprocket chains of the conveyor; and

Fig. VII shows the details of the means which I employ to stabilize the conveyor against the action of the stripper at the region where the coated articles are ejected from the apparatus.

As herein shown, my improved coating apparatus comprises an elongated enclosure 1 affording longitudinal communicating draining and cooling compartments respectively designated comprehensively by the numerals 2 and 3. The enclosure is traversed by an endless conveyor 4 consisting of a pair of spaced sprocket chains 5, 5

having a general horizontal course through the enclosure except at the end of the draining chamber 2 where they are directed downwardly to carry the containers "C" to be coated into the coating solution maintained in a trough or vat 6, see Fig. III. The course of the conveyor is determined by a number of sprocket wheels grouped in pairs and indicated at 7, 8, 9, 10, about which the chains 5 are respectively trained, sagging of the chains being prevented by a double series of idlers 11 suitably supported by the horizontal side rails 12—12 of the structural frame of the machine. The sprockets 7, it will be noted from Fig. II are fixed to a shaft 13 journaled in bearings that are sustained by an extension 14 of the machine frame so that the conveyor is brought to the exterior for convenience of access in loading. Actuation of the conveyor is effected by motion of the sprocket shaft 13, derived through coordination of spur gears 15, 16 see Fig. V, from the main or driving shaft of the machine indicated at 17. The main shaft 17 is equipped with a power pulley 18 capable of being clutched or unclutched by proper shifting of a lever 19 controllable through an associated slide rod 20, which, as shown in Fig. I, has a grasp handle 21 located at a point accessible for convenient manipulation by an attendant. The slide rod 20 is guided in fittings 22 secured to the top of an arcuate protective guard 23 which shrouds the portion of the conveyor 4 that protrudes to the exterior beyond the forward end of the enclosure 1.

Spanning the conveyor chains 5—5 at intervals, are transverse bars 25 each carrying a line or series of clips 26 designed for individually supporting the containers "C" from within. More especially from Fig. VI, it will be noted that each of the clips comprises a group or cluster of spring prongs 27 which are relatively convergent to accord with the tapered configuration of the containers C, and slightly rounded as at 28 to frictionally engage the containers with minimum contact although capable of readily supporting them in suspension as they are carried through the coating fluid in the trough or vat 6. The holder prongs 27 are securely anchored in plates 29 bolted or otherwise secured to the cross bars 25, said plates being cut away centrally at one 110

edge as indicated at 30 in Fig. VI, to afford clearances for a purpose which will become apparent from further description.

In the course of operating the machine 5 an attendant is stationed at the far side thereof as considered in Figs. I and II adjacent the protruding portion of the conveyor 4 to place the containers C on the clips 26 as the latter successively present 10 themselves after rounding the sprockets 7. Under slow progression of the conveyor 4, the containers C are carried horizontally through the two sections or subdivisions 15 of the enclosure until the sprockets 8 are encountered. From this point the direction of travel is vertically downward as best seen from Fig. III so that the containers C are carried into and through the coating solution in the vat 6. As the 20 conveyor 4 travels about the sprockets 9, it is to be especially noted that the containers C make a semi-rotation from a horizontal position as they enter the coating bath, to a corresponding though inverted 25 horizontal position as they emerge from the bath, and that the path defined by the sprockets is such as to effect total submergence of the articles in the bath. As a consequence of the foregoing, complete 30 coating both of the interior and exterior of the containers C is assured, the surplus scooped up during progression through the bath draining back into the trough on the approach of said containers to the horizontal 35 as they leave the trough or vat 6. In order to accelerate expulsion of the surplus, the conveyor 4 is purposely angularly diverted, in the interval between the sprockets 9 and 10.

40 After rounding the sprockets 10, the conveyor 4 retraces a horizontal course through the enclosure 1 to the point of starting. As the coated containers C pass through the chamber 2, any excess drippings are collected upon a sloping apron 31 in the bottom of said chamber and conducted thereby back into the trough or vat 6. When paraffine or the like is used as the coating, I make provision for heating the chamber 2 so as to facilitate drainage of any excess, preferably by disposing a heating coil 32 with one or more vertically disposed convolutions at each side along the 45 return run of the conveyor 4 and at a level proximate the path of the suspended containers C. Flow of the accumulation on the apron 31 is promoted by disposal therebeneath of a coil bank 33 whose longitudinal pipes 34 extend between transverse headers or manifolds 35-36 at opposite ends thereof, as will be best understood from Figs. III and IV. The heating medium is supplied by a main 37 descending from overhead and whereto the side coils 50 are connected in parallel by branch pipes

38 extending from the point of juncture with said main to first bridge the enclosure, and thence downwardly along the sides of the latter to the coils 32. The side coils 32 are in turn jointly connected 70 in series with the coil bank 33, their terminals joining opposite ends of the header 35 of the coil bank 33, as indicated at 39 in Figs. III and IV. This method of coil connection is purposely resorted to 75 with a view toward obtaining the most effective heat distribution.

If desired the heating jacket 40 of the trough or vat 6 may be supplied by a separate pipe connection, but better still to preserve the simplicity of the heating system, the same is herein shown as communicative with the coil bank 33 through a pipe 41 that leads from the center of the manifold 36.

In the passage through the chamber or compartment 3, the coating on the containers "C" is given time to congeal or harden before the latter are ejected in a manner, to be presently explained as the conveyor 4 90 passes to the exterior of the enclosure 1. The side walls 42 of chamber 3 are carried well downward toward its bottom 43 so as to afford the articles the necessary protection against dust though leaving amply proportioned longitudinal openings 44 to insure free circulation of air.

As a means for ejecting the containers C from the apparatus, I provide a stripper mechanism which includes a transverse 100 shaft 45 appropriately journalled in bearings supported by the frame extension 14, said shaft having secured thereon a series of collars 46 wherfrom extend individual stripper fingers 47 (see Figs. II and V) 105 corresponding in number to, and disposed in line with the holder clips 26 on the respective cross bars 25 of the conveyor 4. These fingers 47 normally occupy the inclined position shown with their free ends at a level immediately above the tops of the oncoming containers C. As the containers C pass beneath the fingers 47, the latter are swung in a direction opposed to the movement of the conveyor (as indicated by the arrow in Fig. V, and as permitted by the cut outs 30 in the plates of the clips 26) thereby releasing said containers C from the holder clips 26 to drop into a chute 48 (Fig. I) designed to direct them to a suitable collecting receptacle, not shown. Rocking of the shaft 45 to bring about this result must of course be in timed relation to the movement of the conveyor 4. To this end, the shaft 45 has mounted thereon a roller arm 49 adapted to be influenced by a rotary cam 50 on a stub shaft 51 which is driven by a gear 52 that intermeshes with the gear 15 aforescribed as mounted on the sprocket shaft 13. A contractile spring 53 serves to maintain the

- roller arm 49 at all times in cooperative engagement with the cam 50, while the lower run of the conveyor 4 is stabilized to oppose the action of the stripper fingers 47 by provision, at the region of ejection of the containers C, of side guide brackets 55 Fig. II supported by the frame extension 14 and engaging the sprocket chains 5, as best shown in Figs. II and VII.
- 10 Although I have described my invention in connection with paraffining receptacles of paper, the same may be employed with equal advantages in coating other articles with different surfacings, the nature of the particular coating employed determining the atmospheric conditions which should be maintained within the enclosure to obtain the desired results.
- Having thus described my invention, I 20 claim:
1. In apparatus of the character described, the combination of an enclosure having a vat for coating solution at one end, means for heating the vat and enclosure, an extension at the other end of the enclosure effective for cooling purposes, and means for conveying articles, first, through the vat and heated enclosure to permit draining of any excess solution, and thereafter through the 25 extension for cooling.
2. In apparatus of the character described, the combination of a vat for molten coating solution, an enclosure, means for conveying articles coated with the solution horizontally through the enclosure to permit draining 30 of any excess, heating coils with vertically arranged convolutions at opposite sides of the enclosure in close proximity to the passing articles so as to facilitate draining, an apron beneath the conveying means for collecting and conducting away the accumulation, and a horizontal coil underlying the apron for promoting flow of the coating falling on said apron, the vertical side coils being connected in parallel with the source 35 of supply and jointly in series with the horizontal coil.
3. In apparatus of the character described, the combination of a vat for molten coating solution, a conveyor, clip means on said conveyor each comprising a plurality of spring prongs for frictionally engaging the articles from within to support them during progression through the apparatus, and intermittently rockable fingers for stripping the 40 articles after being coated from the clips and ejecting them from the apparatus.
- In testimony whereof, I have hereunto signed my name at Philadelphia, Pennsylvania, this 29th day of September 1923.

WILLIAM E. BARLOW.
